UNITED STATES PATENT OFFICE

LEO J. LOEFFELMAN, OF ST. LOUIS, MISSOURI

EXPANSION REAMER

Application filed December 30, 1927. Serial No. 243,672.

The present invention relates to the type of tools for truing and enlarging openings and generally designated as a reamer.

The invention provides a reamer including a body, cutters seated in channels formed in the sides of the body, means for moving the cutters longitudinally of the body to effect a simultaneous lateral movement thereof to vary the diameter of the tool, and means for securing the cutters in the required adjusted position.

While the drawing illustrates a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawing hereto attached, in which,—

Figure 1 is an elevational view of an expansion reamer embodying the invention, an intermediate portion of the body being broken away.

Figure 2 is a view similar to Figure 1, partly in section, the right hand cutter being omitted, and its position indicated by dotted lines.

Figure 3 is a detail view of an end portion of the reamer, partly in section, on the line 3—3 of Figure 1.

Figure 4 is an enlarged sectional view on the line 4—4 of Figure 1.

Figure 5 is an enlarged perspective view of one of the cutters.

Figure 6 is a sectional view similar to Figure 4 of a modification.

Corresponding and like parts are referred to in the following description and designated in the several views of the drawing by like reference characters.

The numeral 1 designates the body or stock of the reamer which may be of any determinate length. A pilot 2 is formed at one end of the body 1 by reducing the stock. A shank 3 is formed at the opposite end of the body 1 for convenience of receiving a suitable oper-

ating member, such as a brace, wrench or bar. The end portion of the body 1 adjacent the pilot 2 is reduced to form an annular shoulder 4 which constitutes a shoulder for limiting the movement of a sleeve 5 in one direction. A screw 7 is threaded into the reduced portion of the body 1 a distance from the shoulder 4 corresponding to the length of the sleeve 5 to retain the latter in place. The head of the screw 7 has an eccentric arrangement to admit of securing the sleeve 5 by a binding action upon turning the screw in either direction. The sleeve 5 is milled or roughened upon its exterior to enable the hand to obtain a firm grip thereon when rotating the sleeve to effect adjustment of the cutters. The inner wall of the sleeve 5 tapers and is threaded, as indicated at 8, to engage threaded portions 9 of the cutters 10.

Longitudinal channels 11 are formed in the reduced portion of the body 1 to receive the cutters 10. The inner walls or bottoms of the channels 11 incline, as indicated most clearly in Figure 2 of the drawings, the inclination corresponding to the taper of the inner wall 8 of the sleeve 5. The side walls of the channels 11 converge outwardly and corresponding elements extend parallel lengthwise of the body. This insures contact of the sides of the cutter with the sides of the channels in every adjusted position of the cutters. The cutters 10 are of wedge form in cross section and retained in place by the corresponding outline of the channels, as indicated most clearly in Figures 4 and 6 of the drawings. The cutters 10 taper throughout their length, the inclination corresponding to the inclination of the inner wall or bottom of the channels 11, with the result that the outer faces and cutting edges are parallel, as indicated most clearly in Figures 1 and 2 of the drawings. Each of the cutters 10 is cut away upon its outer side adjacent its upper end, as indicated at 12, to provide clearance. The end portion beyond the recess 12 is reduced and provided with threaded sections 9 to match the inner threaded wall 8 of the sleeve 5. The tool may be provided with any number of channels and cutters, two being shown in Figure 4 and six in Figure 6. The

100

cutters 10 are of tool steel properly tempered. A screw 13 threaded into a side of the body 1 is adapted to have its head engage a side of a cutter and secure the same in the required adjusted position. In the arrangement indicated in Figure 4, a screw 13 is provided for each of the cutters 10. In the arrangement shown in Figure 6 a screw 13 cooperates with two cutters to effect a binding thereof in the channels in which they are seated.

When the parts are assembled, and the sleeve 5 and cutters 10 are free, rotation of the sleeve 5 effects longitudinal movement of the cutters in their respective channels or seats and by reason of the inner faces of the cutters and the bottoms of the channels being inclined, said cutters are moved outwardly or inwardly according to the direction in which the cutters are moved longitudinally of the body. After the cutters have been adjusted to the required position they are made secure by tightening the screws 13 and by turning the screw 7 which effects a binding of the sleeve 5 to prevent casual rotation thereof.

Having thus described the invention, I claim:

1. A tool of the character specified comprising a body having a shoulder, a sleeve rotatable on the body and limited in one direction by said shoulder, a screw threaded into a side of the body and having an eccentric portion in engagement with the sleeve to limit its movement in the opposite direction and to hold the sleeve in adjusted position by a binding action when the said screw is turned, and cutters slidably mounted upon the body and having screw-thread engagement with the said sleeve to be moved thereby.
2. A tool of the character specified comprising a body having a pilot at one end and a shank at the opposite end, and having the end portion adjacent the pilot reduced to form an outer shoulder, and having longitudinal channels in the reduced portion, the inner walls of the channels being inclined and the side walls outwardly converged, cutters snugly fitting within the channels and having thread sections at their inner ends, a sleeve rotatably mounted upon the reduced portion of the body and having its inner wall tapered and threaded to match the thread sections of the cutters, the inner end of the sleeve engaging the outer shoulder of the body, an element mounted upon a side of the body and having an eccentric portion engaging the opposite end of the sleeve and adapted when turned to bindingly engage the sleeve to prevent movement thereof, and screws threaded into the body and adapted to engage the cutters to hold them in adjusted position.

In testimony whereof I affix my signature.
LEO J. LOEFFELMAN. [L. S.]
